SIZE-REDUCING APPARATUS

Robert S. Butler, Claremont, N. H., assignor to
Sullivan Machinery Company, a corporation of
Massachusetts

Application December 31, 1934, Serial No. 759,902

18 Claims. (Cl. 83—9)

My invention relates to material-size-reducing mills, and more particularly to apparatus for reducing material of moderate initial size to the finest commercially desirable sizes, although in 5 its broader aspects no limitation as to material size is to be inferred.

Fine-grinding is a process of increasing commercial importance, and is becoming still more important with the growing use of pulverized 10 fuels. It is accordingly of great importance to provide, for the operation of fine-grinding, as well as for other size-reducing operations, apparatus which will function as efficiently as possible. Among the factors which contribute to efficiency 15 are: abundant discharge area for adequately reduced material; the avoidance of choking of the apparatus; controlled and regulated feed of material to be processed, to the apparatus; the classification of the size-reducing media and the 20 material to be reduced, so that coarser particles of material shall be acted upon by the coarser size-reducing media and finer particles of material by the smaller size-reducing-medium elements; intense activity of the material and the 25 size-reducing media so as to effect a maximum processing rate; the prevention of short-circuiting of the material within the mill, with resultant over-size reduction of part of the material; and assuring that the size-reducing medium shall 30 work upon the material to be reduced in size and not upon itself. The capacity to reduce the power consumption as the processing rate is reduced, is also of great desirability.

It is elementary that choking of a mill can be 35 certainly avoided only when the rate of feed does not exceed the rate of size-reduction and discharge of the material to be processed. It is also elementary that inadequate feed rate means loss of output. A truly self-regulated feed is 40 therefore of great importance, but heretofore has not been found practicable, so far as I am advised, as the secret of taking care of the variables, such as sudden differences in the process- 45 ability of the material to be reduced in size, variations due to voltage changes, for example, in the drive of the mill, differences in moisture content of the material fed, etc., has not previously been discovered. In large mills, such as ball mills, where there is a great deal of spare space fluctuations of the type mentioned could be cared for, but the general inefficiency of the apparatus as a 50 whole and its relatively enormous size and expense, make a simpler arrangement very important.

55 If it is possible to provide a self-regulating feed

in which conditions within the chamber itself control the rate of admission of the material to be reduced, it is obvious that the necessary control can be secured; and it is an object of my invention to provide for this result, and the apparatus herein described will accomplish it. 5

Rapidity of discharge of the fully processed material is obviously of great importance, as material which is adequately reduced in size should be gotten out of the mill to make place for new 10 material. Maximum discharge can be obtained by the provision of a rather shallow, wide chamber, and, as will later be apparent, great activity of the material in process contributes to rapidity of discharge; and my invention has for one of 15 its objects the provision of improved means for effecting maximum discharge rate, and will be found to provide for very rapid escape of the fully processed material.

The classification of material and size-reduc- 20 ing media (meaning by the latter, balls of various sizes, or other shapes of material of sufficient hardness to be used in the size-reducing operation) according to size, is important, for when large particles of material can be subjected to 25 the action of the larger and heavier reducing elements and the partially reduced material may be subjected to the action of the smaller reducing elements, it will be found that more useful blows per unit of time will be struck and the 30 blows will be better adapted to the work. Furthermore, the attrition effect will be a maximum in a classified arrangement of material and reducing units as described. Such a classification of the 35 material and of the reducing media will be found to occur to a maximum degree where centrifugal action takes place, for the denser material, that is, the material of small unit size, will move as far as possible from the axis of oscillation due to its greater density, when the action and circum- 40 stances are such as will permit this arrangement and rearrangement, and thereby size-reduction will be effected with maximum efficiency.

Another feature of very great advantage will be found to lie in the employment of an oscillating 45 chamber, provided, of course, that chamber be arranged so as positively to impart to the contents thereof arcuate movement, due to the tendency of the chamber contents to travel at all times at a tangent to the direction of chamber oscillation; 50 and with an arcuate chamber form it will be found that accordingly there is heavy pressure, particularly with substantial quantities of material and reducing media and considerable weights thereof, of material on the bottom of 55

the chamber, with the result that attrition is exceedingly effective in the size-reducing operation.

From one of its aspects, my invention includes the feature of providing for a certain maximum quantity, by volume, of material within a processing chamber at any time, and means has been found whereby this can be accomplished merely by the proper shaping and proportioning of the 10 chamber. The chamber is proportioned fundamentally so that the load therein, that is, the mixture of size-reducing medium and material to be ground, may be treated as a coherent mass. In effect, the contents may be thought of satisfactorily as a plastic piston of mingled media, of 15 changing compactness and density at different points in the processing chamber cycle of movement. The chamber dimensions with reference to length are desirably limited so that the free 20 play, so to speak, of the material contained therein will not exceed a certain value. When the chamber is receiving no material to be reduced and contains reducing medium only, if such 25 quantity does not exceed the desired maximum it will be found that the reducing medium will not absorb more energy than that due to friction between it and the floor and walls of the chamber. When material to be reduced is added 30 at the proper rate and the quantity of mixed material within the chamber increases so that the free play again attains the proper value, it will be found that maximum reducing efficiency 35 will be attained, although substantial variation from this figure will not result in greatly reduced efficiency.

The vertical height of the chamber should be determined in such a manner that the piston-like action may be attained. Obviously, the actual height will depend in great measure on the quantity 40 of material contained in any given chamber, on the length of the chamber, etc.

At this point some of the practical conclusions from the foregoing analysis may be summarized. A pivotal chamber is desirable because classification 45 and dispersion of the material are thereby enhanced; attrition is greatly increased; feed can take place at a point of little movement, where feed is arranged at or near the axis of oscillation of the chamber; internal classification 50 of medium and material is possible, and centrifugal force may be used to a maximum degree. An arcuate chamber form is desirable because of the uniformity of action, its efficient cooperation in control of feed, the increased attrition which 55 results from the tangential tendency of movement of the material to be processed and of the reducing medium, the reduction in power necessary to operate the mill through return of energy to the driving apparatus because the tangential 60 pressure of the load moving along the arcuate bottom of the chamber tends to resist deceleration of the moving system, etc. Feed should be regulated to avoid choking, and is best controlled from within the mill. Discharge area should be 65 a maximum. The load should be adapted to the design of the mill and maintained not in excess of the efficient maximum. Obviously, lightness is an important feature. Single or plural chambers may be used, with staging if desired.

70 The foregoing statements as to preferable characteristics are not to be understood to exclude as embodiments of my invention mills lacking certain of the enumerated features, and all rights with respect to all constructions falling within 75 the scope of the appended claims and/or em-

bodying any of the aspects of my invention herein described, are expressly reserved.

For the purpose of establishing a vocabulary for the reader discussion of the invention, it may be said that the terms "medium" and "media" will be used from time to time to designate the freely moving reducing means contained within the processing chamber. Such media may consist of chrome or other alloy steel balls of various sizes, steel shapes other than 10 spherical, and particles, so to speak, of various sizes of material having hardness appropriate to the reducing action required. "Stroke" will be employed to designate the range of movement of the processing chamber in its path. "Play" 15 means the free travel of the concentrated load between its position when concentrated in one end of the processing chamber and the other end of the latter. As will later be more fully pointed out, play from 1.5 to 1.75 times the stroke is a 20 very desirable value, but when less sharp impact is required, smaller play is very satisfactory, and higher values are not prohibited. "Load" will be used to designate the combined mass of reducing medium and material to be reduced in size. 25 Loads less than fifty percent of chamber volume are relatively undesirable; and a load of approximately sixty-six percent of the chamber volume will provide very effective reducing operation. "Reduction" will be used as a general designation for the various operations of crushing, pulverizing, etc., and in the form of "reduction" or "reducing" will be generally used to cover all of the various types of operations just individually mentioned.

With a properly designed chamber, the load will act as a valve. If a load decreases below the maximum desired, due to a decrease in feed rate, power consumption will decrease, the rate of decrease being governed by the rate of decrease in load, that is, the rate of discharge. When the load consists solely of reducing media, the play with a properly designed chamber will increase to such a degree that the load no longer will derive from the chamber, other than from friction upon the chamber walls, any tendency toward movement, and therefore the power consumption will be only that requisite to overcome the friction of the moving parts of the apparatus. When feed again commences, the load will increase, the play will shorten, and the load activity will increase until the load has reached its maximum point of efficiency, where it will remain due to the proportioning of the chamber and supply passage design.

From one aspect, my invention comprises a chambered mill element, a relatively movable chamber-enclosed reducing medium associated therewith, and means for effecting relative movement between the chambered element and the associated medium involving reversals of movement. Preferably, rapid oscillatory movement will be provided, and, very desirably, pivotal movement of the chambered element will be selected. Arcuate chamber form and graduated size of the relatively movable reducing media are very advantageous. While, obviously, different pivot locations may be selected for the chambered element, a pivot location near the point of initial material ingress facilitates feed; and a top pivot 70 improves smoothness of operation, makes easier the discharge of processed material and promotes attrition. Arcuate chamber form in conjunction with pivotal chamber movement increases size reduction by attrition and conserves power. The 75

use of larger media and of impact for reducing larger material particles, and quantities of small to fine media for pulverizing provides a number of impacts more or less proportionate to number 5 of material particles. Chamber oscillation, as compared with oscillation of the internal reducing media facilitates drive and simplifies mechanical construction. Top, bottom, end, side discharge: all may be used, and in appropriate 10 combinations and with orificed plate, grid, screen, laminated or other or combined chamber wall construction. All these features are available with my invention, and all the features disclosed in the discussion of preferred constructions are 15 within the contemplation of my invention from its several aspects.

An object of my invention is to provide an improved size-reducing unit. Another object of my invention is to provide an improved apparatus 20 for the purposes stated which will be relatively light, require relatively little power, and yet develop powerful forces. A further object of my invention is to provide an apparatus of the character specified in which quite high velocities of 25 the reducing media may be obtained and in which through reversals of direction a much greater impact effect and reducing activity of the reducing media may be obtained when desired, and a reducing action adapted to the material to be reduced secured. Still another object of my invention is to provide an improved apparatus of the type specified in which maintenance expense will be reduced to a minimum. Yet another object of my invention is to provide an improved 30 apparatus of the type specified in which automatic feed without interruptions in the operation of the device may be effected, and in which the rate of feed will be automatically controlled so as to prevent choking and to maintain a high 35 degree of efficiency of reducing operation. Still another object of my invention is to provide an improved apparatus of the type mentioned in which attrition, as well as impact, may be availed of in very large measure. Yet another object of my invention is to provide an improved apparatus of the type described in which the fineness of the product may be readily automatically controlled, and products insufficiently reduced may be returned to the action of the mill. Still another object of my invention is to provide an improved reducing apparatus, in which, by mechanism inherent in the apparatus itself, a variation in the fineness of the end product may be readily effected. Still another object of my invention is to provide an improved mill in which an improved movement of the parts cooperating 45 in the reducing action is incorporated, whereby, with a device lighter by far than any present commercial installation, a higher output per unit of weight, per unit of space, per unit of power, and per unit of time, may be obtained. Yet another object of my invention is to provide an improved mill in which the power consumption will be greatly reduced as the feed rate diminishes or 50 feed is discontinued. Still a further object of the invention is to provide an improved mill in which size-reduction will be effected not only within the processing chamber, but at the zone at the bottom of the material-feed connection, 55 and to a certain extent within the feed connection also. Still another object of my invention is to provide an improved oscillatory mill. Yet another object of my invention is to provide an improved oscillatory mill in which impact and attrition may be combined in the effecting of re-

duction of the material to be reduced, in a manner never previously attained. Still another object of my invention is to provide an improved oscillatory type mill having provision for effecting continuous feed and discharge. Still another object of my invention is to provide an improved rocker type mill having improved discharge means whereby discharge is effected, at least in part, in a direction opposite to the normal action of centrifugal force on the material being reduced. Still another object of my invention is to provide an improved rocker type mill in which a very wide range of variation in the charge of size-reducing elements shall be possible without seriously impairing the efficiency of the apparatus 10 or changing the quality of the product, whereby even negligent attention to the operation of the mill will not be able to result in an unusable product or a gross waste of power. Still another object of the invention is to provide a mill having 20 provision whereby during extended periods of reduced demand for its product the mode of operation thereof may be altered to diminish the required power input while still providing an adequate but reduced quantity of end product of 25 the same qualities as is produced when the mill is being operated at maximum capacity. Other objects and advantages of the invention will hereinafter more fully appear.

In the accompanying drawings, in which, for 30 purposes of illustration, two illustrative embodiments of the invention are shown,

Fig. 1 is a side elevation, with parts broken away, showing a preferred illustrative form of my invention incorporated in the form of an improved coal pulverizer.

Fig. 14 is a vertical section showing the pulverizing chamber oscillating mechanism, the section 70 being taken on a plane corresponding to the line 14—14 of Fig. 13.

Fig. 15 is a vertical transverse section on a plane corresponding to the line 15—15 of Fig. 9, showing a portion of the driving mechanism 75

for the pulverizing chamber oscillating mechanism.

Fig. 16 is a section on the intersecting planes corresponding to the line 16—16 of Fig. 12.

Figs. 17 to 20 inclusive are diagrammatic views showing different relative positions of the pulverizing chamber and its contents.

Referring first to Figs. 1 to 8, inclusive, of the drawings, it will be observed that in the illustrative embodiment of the invention therein disclosed, a frame, generally designated 1 and which comprises a base portion 2 and three upright walls 3, 4 and 5, is provided. The walls 4 and 5 are connected by end wall portions 6 and 7 to form a chamber 8 in which the driving apparatus is enclosed in part. The walls 3 and 4 are connected by top, transversely extending members 9 and 10 which rigidly space the walls 3 and 4, and these walls are further connected by a hollow tubular member 11 which provides a housing for a transversely extending crank shaft 12, which is journaled within suitable sleeve bearings 12'. The member 11 is provided with a lateral portion 13, which has a hand-hole cover 13' thereon so that access may be had to the space within the member 11 to permit the removal or replacement of the bearings 12' when desired. Suitable chambers 14 surround the bearings and are adapted to be supplied with lubricant through openings 15, while the outer bearing 12' is sealed by a felt gasket or washer 16 suitably held in position, as by a cover 17. The crank shaft 12 has a driving pulley 18 to which power may be supplied through suitable driving connections, as for example by a belt 19 driven from any suitable motor, not shown; and this shaft serves to rotate a crank disc 20, from which a drive pin 21 projects eccentrically. The pin 21 is connected by a connecting rod 22 with a pin 23, which may be positioned in the desired one of the openings 24 in a depending arm structure 25, which at its upper end is fixedly connected to a transverse hollow shaft 26. Upon the hollow transverse shaft 26, which is suitably supported in bearings 27 and 28 carried by the frame members 3 and 4, there is supported a size-reducing or pulverizing chamber member generally designated 29. The hollow shaft 26 at one end thereof—the end opposite the point of connection of the arm structure 25—communicates freely with the interior of a supply chute 30, and the lower wall of the hollow shaft member 26 is cut away as at 31 to provide an opening, through a gradually expanding radial feed passage 32, into the interior space 33 of the pulverizing chamber member 29. The pulverizing chamber member 29 may be built in any suitable manner—whether of plates suitably cut, bent and welded, or parts bolted together, of built-up construction using wall elements stacked, so to speak—to produce perforated or foraminated walls through which discharge is desired (for which construction see my copending application, Ser. No. 759,906, filed of even date herewith), or otherwise. Herein, this pulverizing chamber is shown as built of welded plate, being made up of a series of supporting plate members 35, welded or otherwise suitably secured to the hollow shaft member 26, a bent plate member 36 which forms the bottom, ends and lateral top portions of the chamber, which plate is welded to the members 35, and a pair of end plates 37 and 38 welded or held, as by machine screws or the like, to the most widely spaced and heavier ones of the elements 35 and 36. For the purpose of providing for discharge of adequately pulverized ma-

terial, numerous arrangements and provisions may be made. In this form of my invention I have shown provision for a very large discharge area, and it will be observed that the plate 36 substantially throughout its length, and also the side plates 37 and 38, are provided with discharge orifices or slots, so that top, bottom, end and side escape of the pulverized material may be made possible. The discharge orifices in the plate 36 are designated 36' and those in the plates 37 and 38 are designated 37' and 38'.

Appropriate liners, conformed to the shape of the inner walls of the pulverizing chamber and made of chrome-alloy steel or other material having the necessary wearing qualities, or, if steel is detrimental to the process, other suitable material, may be provided, but as such construction will be obvious to those skilled in the art, the drawings are not complicated by the showing of this additional feature.

The size-reducing pulverizing chamber will be noted to move arcuately about the axis of the hollow shaft 26 between the side walls 3 and 4, and a suitable relatively light, arcuate pan or bottom enclosure member 39 is bolted or clamped as at 40 to the opposite side members 3 and 4 and provides, as it were, a bottom and end walls for a rocker chamber 41. The top transverse members 9 and 10 support an upright, upwardly-tapering discharge chamber cover 44 which supports at its top apparatus for maintaining a pressure differential between the space within the reducing chamber proper and the space surrounding the latter. The construction may obviously vary, but for purposes of illustration there is shown a discharge connection 45 supported on the top of the member 44 and at its upper end supporting a further discharge connection 46 whose interior communicates with a discharge line 47 in which a draft of appropriate intensity is produced by suitable means, as for example, a blower or air jet device 48. It is to be understood, of course, that the blower device shown is merely illustrative of means for placing the interior of the chamber surrounding the reducing chamber 45 under an appropriate suction, and any other suitable means, such as a fan, a properly screened suction pump, or the like, could be used instead of the apparatus shown. The interior of the discharge connection 45 is divided into a plurality of parallel upright discharge connections 50, 51, 52, 53 by vertical parallel septa 54; and dampers 55 suitably manually or otherwise controlled are provided, herein at the base of the vertical discharge connections, to enable appropriate draft modulation. The several discharge passagcs extend upwardly, still separated from each other by septa 56 formed in the discharge chamber 46, nearly into alignment with the bore of the discharge connection 47 extended rearwardly.

Within the interior 33 of the reducing chamber member 29 there is enclosed an appropriate free reducing medium, herein in the form of a charge of balls, shown at 57, which may occupy, depending on conditions, say, from twenty to sixty percent by volume, of the interior of the chamber 33. These balls may vary in size from somewhere around an inch in diameter down to a size just too large to pass through the grid openings 36', 37', 38'. The member 29 is provided with a suitably covered lateral opening 58, and the frame member 3 has a suitably covered lateral opening 59.

It will be appreciated that the reducing (pulverizing) forces generated within the size-reduc-

ing space 33 will depend upon the velocity of the chamber, and the masses of the relatively moving parts, and the times of coaction between these parts. The velocity of the chamber will determine the velocity of the contained size-reducing medium and the intermingled charge of material to be pulverized. The chamber velocity will be determined by the R. P. M. of the crank shaft, the throw of the crank shaft, and the nature of the connection with the pendulum. Essentially, the force of the blow as affected by the mass of the moving parts, will be controlled by the mass of the moving chamber contents, for the direct power drive of the chamber will always cause the latter to have an "equivalent mass" greater than that of the free body within the chamber. The time of coaction between the chamber walls and the chamber contents will affect the nature of the coaction and, in a measure, the force of the coaction, for, if chamber and contents meet each other at the instant when each is traveling at maximum velocity but in mutually opposite direction with respect to the other, a very high degree of sharp impact and maximum value due to the kinetic energy of the parts will be obtained. Obviously, anything from this condition down to a condition where coaction between the freely moving chamber contents and chamber wall takes place substantially at the so-to-speak dead center positions, is a possibility; and the designer of the individual machine will bear in mind the characteristics of the material to be reduced in size, in selecting values. The net free play of the chamber contents (load), with the device illustrated, may be approximately thirty-three or thirty-four percent of chamber length, running somewhat lower than the difference between unity and ratio of the length at one side of the opening 32 plus the width of that opening to the whole chamber length, due to the fact that the chamber contents will not act like a piston of uniform cross section but will instead progressively fill to its full vertical dimension the chamber from points adjacent the end of the chamber back towards its center, as the material surges within the chamber, and accordingly material will flow down the sloping surfaces of the chamber contents in excess of the quantity which would enter were the rear edge of the chamber contents always truly radial. It is important that the chamber contents shall fill the chamber from top to bottom at each end of their travel within the chamber, and it will be noted that as the chamber is oscillated there will be a classification of material and of size-reducing medium in accordance with relative density, the larger material particles and size-reducing elements being nearer the axis of oscillation and the finer material fragments and finer size-reducing medium occupying positions adjacent the bottom wall of the chamber, with the result that as the material is reduced to the desired fineness it automatically approaches the discharge area; and, moreover, large size-reducing elements act on large particles, and small size-reducing media act on finer particles, and thereby the impact is adapted to the work and the blows are delivered where they will do the most good.

With this discussion of the general structural features and phenomena which characterize the illustrative embodiment of the invention which has been described, the mode of operation may be set forth in further detail. It will be evident that, depending upon the proportion of the parts, size of the balls, the weight of the ball charge,

the velocity of the pendulum, and the number of oscillations the same goes through per unit of time, and other variable factors referred to above, the designer may provide a mill which is adapted for the size-reduction of substantially any material. The mill so far specifically described and illustrated is particularly advantageous for pulverizing coal but it will be obvious that its utility is in no sense confined to size-reducing that material.

The air jet 48 will be set in operation and regulated in accordance with the rate of supply and pulverization of the coal, so that a draft from a few inches of water upwards, as may be desired, may be maintained through the machine. Coal to be pulverized will be fed in a suitable pre-conditioned form to the hopper or chute 30, and will pass at a more or less uniform rate inwardly through the left-hand end in Fig. 2 of the shaft 26, and will then pass down through the passage 32 into the chamber 33, where it will be subjected to the size-reducing action of the medium 57, as previously described. As the balls and coal intermingle and the mixture is rapidly thrown from end to end of the chamber 33 as the latter is caused to pass many hundreds of times per minute through an oscillatory cycle, the chamber contents will act almost as a piston as they pass across the mouth of the passage 32, and thereby control the rate of access of coal to be pulverized into the chamber 33. Moreover, due to this piston-like action, there will be provided a continuous forcing of air entering the chamber through passage 32, outwardly through the orifices 36', 37', 38', and so a highly efficient discharge of fully reduced material. The material passing through these discharge orifices and entering the chamber 41 will pass upwardly past the dampers 55 and through the active passages 50, 51, 52, 53, and out through the connection 47 to a suitable classification device (not shown), from which inadequately reduced material will be returned and reenter the chamber with the feed. Due to the arcuate form of the chamber and its arcuate path of movement, and the tendency of the chamber contents to travel in straight lines tangential to the arcuate path of the chamber, a very effective reduction in size of the material to be ground will be effected due to attrition, and power consumption will be minimized. In the event that the play be made approximately 1.5 times the stroke of the chamber, and with the chamber contents as they will be maintained automatically, provided adequate feed is effected to the hollow shaft 26, a very high rate of size-reduction will be effected due to the development of the maximum usable energy within the chamber. However, if the feed is reduced so that less rapid size-reduction necessarily results, it will be evident that a reduced power consumption will take place, and accordingly that the mill is capable of operation efficiently to meet various load requirements. It will be evident from what has been said above, that so long as material is fed to the hollow shaft 26 and the mill chamber oscillated, there will be provided a continuous size-reducing action, safeguarded against any possibility of choking of the mill, by the automatic feed control, and with, as it were, an automatic reduction in power with reduced material supply to the chamber.

It will be evident that while this device is described in connection with the embodiment illustrated as especially arranged for dry size-reduction, suitable modifications of the construction to adapt it to wet size-reduction will be within

the capacity of any designer of ordinary skill; the arrangement for carrying away the fully reduced material being essentially the only change which would be necessary. Indeed, the only necessary change to permit this different form of size-reduction would be to provide, instead of the pneumatic evacuation of the dry dust, a gravity discharge through an appropriate bottom opening of the wet pulp from the chamber 41.

Referring now to Figs. 9 to 16, inclusive, of the drawings and to the other illustrative embodiment therein disclosed, it will be noted that a frame 61, which comprises a bed 62, a lateral wall 63, another lateral wall 64 to which a housing 65 is connected, and spaced transverse portions 66, provides a suitable support for the size-reducing mechanism. The wall portions 63 and 64 are interconnected, as by welding, with the opposite ends of a tubular member 66', within which suitable sleeve bearings 67, 67 are arranged, and having a lateral portion 68 provided with a hand-hole cover 69 so that access may be had to the interior of the member 66' to permit the removal or replacement of the bearings 67 when desired. Suitable chambers 68' surround the bearings and are adapted to be supplied with lubricant through openings 69', while the outer bearing 67 is sealed by a felt gasket or washer 70 held in position by a cover 71. A shaft 72 having a driving pulley 73 to which power may be supplied through any suitable driving connection, as by a belt 74 driven from a suitable source of power not shown, serves to rotate a crank disc 75, from which a pin 76 eccentrically projects. The pin 76 is connectible by a pitman or connecting rod 77 with a pin 78, which is positionable, depending upon the desired range of oscillation, in one or another of a series of mounting holes 79 or 79'. The mounting holes are arranged in a depending arm 80 which is secured at its upper end to a hollow tubular shaft 81. The shaft 81 is journaled at its end nearer the arm member 80 in a cap-bearing 82 and at its opposite end in a cap-bearing 83. The bearing 82 is carried by a projecting boss 84 formed on the wall 64 and extending into a chamber 85 formed between the members 64 and 65 and having a cover 86 suitably secured thereto to provide a sealed chamber in which the drive mechanism, including the flywheel or crank disc 75, the connecting rod 77, the arm 80, and the driven end of the shaft 81, are disposed. A suitable hand-hole cover 87 is provided in the wall member 65 to permit access to the variably positioned pin 78.

Within the space 90 formed between the wall portions 63 and 64 there is carried by the hollow shaft 81, between the bearings of the latter, an oscillatable member 91 which in its entirety may be referred to as a pendulum member because of the fact that it carries below its center of oscillation a chamber-forming portion 92 which corresponds in position to the weight of a pendulum, being offset from the axis of oscillation by a greater distance than any other portion of the oscillating structure (except the lower end of arm 80). The pendulum 91 comprises a more or less cylindrical body 93 having walls 94 coaxial with the walls of the hollow shaft member 81, and supported by end walls 95. The peripheral wall of the member 93 is cut away at the upper portion thereof as best shown in Figs. 12, 13 and 16, to provide an approximately rectangular opening 96, the function of which will be later described. The lower part of the peripheral wall 94 of the body 93 is provided with an opening 99, 78 to which there leads the inwardly tapering or

wedge-shaped passage 100 having walls 101 extending from the peripheral wall of the hollow shaft member 81 to the peripheral wall at its lowermost portion of the member 93. A passage rectangular in outline and designated 104 connects the interior of the shaft 81 with the wedge-shaped passage 100. The discharge end 105 of the passage 104 opens into the interior 106 of a pendant chamber-forming body 107, which is secured as at 108 in any suitable manner to the lowermost part of the member 93. The lower walls of the member 93 at opposite sides of the passage 100 are provided with a series of long, narrow, circumferentially-extending slots 110, which may desirably be somewhat less than $\frac{1}{8}$ " 15 in width for the particular size and type of size-reducing apparatus which constitutes the illustrative embodiment. These slots, of course, it will be noted, connect the space within the member 93 and the chamber 106. The chamber 106 is herein 20 approximately a quadrant in angular extent and has a lower imperforate wall 112 struck on an arc from the center of the axis of oscillation of the shaft 81. It has end walls 113 which lie in planes extending radially from the axis of oscillation of the hollow shaft 81. These walls may also advantageously lie in planes which intersect in a line below the axis of oscillation is desired. The ends 113 and bottom wall 112 are reinforced by flanges or webs 114. The chamber may be suitably lined with replaceable liners if desired, as for example, by liners of chrome or other suitable alloy steel or any other suitable material—a rubber liner being desirable under some conditions; but as the construction of such elements is well known to those who are skilled in the size-reducing art, they will not be described or depicted. A suitable elbow connection 116 is mounted on the frame member 63, having a mouth extending into the interior of the hollow shaft 81, and provided with a wide-mouthed chute 117 for receiving material which is to be reduced in size, and delivering the same, through the elbow 116, into the interior of the shaft 81. Upon the top of the frame heretofore described, and suitably held to the cross members 66 thereof is an upright frame, supporting on pedestal members 119, 119 a discharge connection 120, at whose upper end there is mounted a further discharge connection member 121 whose interior communicates with a discharge line 122 in which a draft of appropriate intensity is produced by a blower device 123. It is to be understood that here also the blower device is merely illustrative of means for placing the interior of the size-reducing apparatus under an appropriate suction; and any other suitable means such as a fan, an appropriately screened suction pump, or the like, could be used instead of the apparatus shown. The pedestals 119 support arcuate walls 125 with whose interior the peripheral surfaces of the cylindrical wall 94 of the oscillating member 93 make a close fit. These arcuate walls 125 extend upwardly from a horizontal plane, herein shown as including the axis of the hollow shaft 81, through an angle of somewhat more than 45°, and terminate in the upright parallel end walls 126 of the discharge connection element 120. The interior of the discharge connection 120 is divided into a plurality of parallel, vertical discharge connections 127, 128, 129, 130 by vertical, parallel septa 131; and dampers 132 suitably manually controlled or otherwise are arranged in the top of the pedestal member 119, one for each passage 127, 128, 129, 130, for closing one 70 75

or more of these discharge passages to provide appropriate draft modulation. The several discharge passages extend upwardly, still separated from each other by septa 131' formed in the discharge member 121, nearly into alignment with the bore of the discharge connection 122 extended rearwardly. The pendulum member may advantageously be provided with an upwardly extending fan or paddle member 140, secured thereto opposite the supply passage 100 and midway between the sides of the lateral opening 96.

The fact that suction devices are shown and described for the carrying away of the dry size-reduced material does not imply that means for effecting a pressure differential by superatmospheric pressure is not within the contemplation of the invention. Indeed, any means for effecting processed material movement by means of a fluid capable of maintaining it in suspension is to be understood to be within this aspect of the invention.

It will be noted that air may enter the open end of the hollow shaft 81 with the material supplied through the chute 117, and may pass through the passage 100 down into the pendulum chamber 106. It may pass outwardly through the opposite ends of the pendulum chamber through the grids 110, around the arcuate portions lying between the coaxial walls of the hollow shaft member 81 and the casing 93, upwardly through the opening 96, upwardly through the discharge passages 127, 128, 129, 130, and through the discharge connection 122. Aside from the restriction provided at the opening 104, there is arranged a progressive increase in cross sectional area in the various passage portions between the point of inlet and the chamber 121, so that there is a retardation of the rate of flow of the air, i. e. a progressive diminution of the velocity of the air, as the latter passes through the apparatus and up through the discharge conduits 127, 128, 129, 130, if all dampers are open. Obviously, the dampers may be set to alter this condition, and the area at practically all points between primary supply and final discharge may be varied to meet different operating conditions.

Within the chamber 106 there is provided a charge of balls, which may occupy, depending on conditions, from twenty to sixty percent by volume of the interior of the chamber 106. These balls may vary in size from an inch or more in diameter down to a size just too large to pass through the grid openings at 110, in the particular mill illustrated and for coal pulverizing.

The mode of operation of this apparatus will be readily understood from what has been described, but may be summarized, with reference to coal or other material to be processed as follows. The air jet 123 is set in operation and regulated in accordance with the rate of supply and size-reduction of the coal so that a draft of from a very few inches of water upwards as may be desired will be maintained through the machine. Coal to be processed will be fed in a suitably pre-conditioned (by screening) form to the hopper 117, and will pass at a more or less uniform rate in through the left-hand end (in Fig. 13) of the shaft 81, and pass down through the expanding passage 100 into the ball chamber 106, where it will be subjected to the size-reducing action of the balls. As the balls and coal intermingle and the mixture is rapidly thrown from end to end of the chamber 106, as the latter is caused to pass many hundreds of times a min-

ute through an oscillatory cycle, the moving mass of reducing agent and material to be reduced in size will act almost as a piston as it passes across the mouth of the passage 100 and over the gridded discharge openings at the top wall of 5 the casing 106, and will aid in the provision of a definite flow of air through the apparatus. The ends 113 of the chamber 106 will direct, as they are impinged upon by the moving contents of the chamber 106, the latter downwardly, thus increasing attrition, and so cause a very effective attrition and size-reducing action. As the material particles in the charge are reduced in size, the heavy balls will displace continuously upward the finely divided and much lighter coal dust, 15 and as the latter reaches a sufficient degree of fineness so that the same is capable of being supported in the light draft of air passing through the machine, the most finely divided coal will be drawn upwardly out of the size reducing chamber 20 and pass around the outside of the shaft 81 and enter the discharge stacks 127, 128, 129, 130. The fan or paddle element 140, undergoing a motion similar to but opposite in phase to the chamber 106, will act upon the rising columns 25 of air laden with pulverized coal and deflect downwardly, as it were, striking them rearwardly, the heavier particles of dust which are tending to be raised by the air current and to pass out of the machine. Because of the decreasing rate 30 of flow resulting from the enlargements of the successive cross sections of the passage forming means, there will be a reduced lifting power in the air stream, and only the most finely divided (200 mesh and smaller) particles of coal will 35 tend to pass completely out of the riser stacks 127, 128, 129, 130 and enter the discharge connection 122. There will be a constant reverse flow, as it were, due to the fall of the heavy particles back into the chamber 106 and upward passage of the lighter particles, and accordingly only the properly conditioned, that is, reduced, coal will pass from the machine.

For the purpose of illustrating certain of the phenomena which occur during the operation of 45 the mill, reference may be had to the diagrammatic showings of Figs. 17 to 20.

In Fig. 17 the mill chamber, which is shown in the form of chamber 33 merely for the purpose of illustration, contains only the charge of size-reducing media 51. The chamber is illustrated at one of its extremes of movement, and it will be observed that the charge of size-reducing media does not contact at that moment with either end of the chamber. The inertia of the 55 charge is so great, and the forces imparted thereto solely by the friction thereof on bottom and sides of the chamber are so relatively small, that in the absence of the feed of material to the chamber, and indeed in the absence of substantial 60 feed of material to the chamber, there is no contacting of the charge or chamber contents with the chamber ends, and therefore there is exceedingly low power consumption during the "no load" operation of the mill.

Figs. 18, 19 and 20 are diagrammatic views showing the chamber and its contents in three different positions. Fig. 18 shows the chamber at one of its extreme positions of travel, and the chamber contents in this figure comprise not 70 only the charge of size reducing media but the normal quantity of material to be processed mingled with the size-reducing media. At the particular position of the parts shown, the chamber contents are still moving toward the right 75

but have not as yet contacted with and compacted themselves in the right-hand end of the chamber, which is, so to speak, on right-hand "dead-center" position. Obviously, depending upon various factors of design, the chamber contents may be more or less removed from their extreme right-hand position, or may even, where a very low amount of impact is necessary, have substantially attained their full right-hand end position, in the position of the chamber which is shown in Fig. 18. In Fig. 19 the chamber has reversed its travel and is now moving toward the left and has attained approximately mid-position. The chamber contents—size-reducing media and material in process—are compacted in the right-hand end of the chamber, and a certain amount of feed is taking place at F through the opening 32, past the face of the compacted chamber contents. At this moment the chamber contents and the chamber possess substantially identical velocities, and as the chamber commences to slow down due to the characteristics of the driving mechanism therefor, the chamber contents move more rapidly than the chamber walls, and a condition will shortly result such as is shown in Fig. 20, where the chamber is illustrated in a position in which its velocity has begun to decrease, with the result that the contents are moving away from the then-rearward end of the chamber and reducing the distance between their forward face and the end of the chamber which is then in advance of the moving chamber-contents. In this position of the chamber-contents and chamber, it will be evident that the feed through the opening 32 is cut off except to such an extent as may occur through the sifting of finer particles of material into interstices between the larger, uppermost material fragments and size-reducing media at the top of the moving mass of chamber-contents.

It will be appreciated that there is size-reduction, taking place between the upper surface of the chamber-contents passing beneath the mouth of the connection 32 and the lower surface of the material which fills the feed passage 32.

The foregoing diagrammatic views illustrate clearly the "no load", feed-control, classification, and very effective size-reducing features of my invention.

It may be added that between the opposite end faces of the feed connections there will also be a substantial amount of size-reduction of the larger pieces in the case of more friable materials, due to the impact action between such faces and the material moving through the feed passage.

From the foregoing description, it will be evident that I have provided a very efficient, durable, simple and economical size-reducing device, adaptable to the size-reduction of substantially any material, and one which is self-regulating as to feed and self-limiting as to power consumption. As the advantages are fully set forth above, further detailed statement with respect thereto is not essential at this point.

While I have in this application specifically described two forms which my invention may assume in practice, it will be understood that these forms are shown for purposes of illustration only, and that the invention may be modified and embodied in various other forms without departing from its spirit or the scope of the appended claims.

What I claim as new and desire to secure by Letters Patent is:

1. In a mill, a frame, a size-reducing chamber supported by said frame for swinging movement, means including a feed passage a portion of which surrounds the axis of chamber swing for feeding material to said chamber downwardly through the top thereof at a point spaced from the ends thereof, size-reducing media in said chamber, means for swinging said chamber on its axis through a predetermined arc to effect size-reducing cooperation between said size-reducing media and said chamber, said chamber having discharge orifices for size-reduced material, and means for removing material discharged from said chamber through said orifices including means for providing for the flotation of adequately size-reduced material upwardly at the opposite sides of the feed passage portion surrounding the axis of chamber swing.

2. In a mill, a frame, a size-reducing chamber supported by said frame for swinging movement, means including a feed passage a portion of which surrounds the axis of chamber swing for feeding material to said chamber downwardly through the top thereof at a point spaced from the ends thereof, size-reducing media in said chamber, means for swinging said chamber on its axis through a predetermined arc to effect size-reducing cooperation between said size-reducing media and said chamber, said chamber having discharge orifices for size-reduced material, and means for removing material discharged from said chamber through said orifices including passage forming means fixed relative to said chamber and undergoing movement with the latter for providing for the flotation of adequately size-reduced material upwardly at the opposite sides of the feed passage portion surrounding the axis of chamber swing.

3. In a mill, a frame, a size-reducing chamber whose ends are higher than its middle when said chamber is in mid-portion in terms of its motion, said chamber supported by said frame for swinging movement about an axis located above its middle when said chamber is in such mid-position, means for oscillating said chamber through a predetermined arc about said axis, means including a downwardly extending passage and a passage surrounding said axis for supplying material to be reduced to said chamber, and means for conducting size-reduced material from said chamber including walls in fixed relation to said chamber and undergoing movement with the latter and cooperating in providing upwardly extending passages opening into said chamber and lying to the opposite sides of said material supplying passages and terminating above the top of the latter.

4. In a mill, a frame, a hollow shaft supported by said frame for oscillatory motion about its axis, means for oscillating said shaft upon its axis through a predetermined arc, a size-reducing chamber member supported below said shaft for oscillation with the latter, means connecting the interior of said shaft with the middle of said size-reducing chamber, means providing a pair of discharge passages for material reduced in size in said chamber extending to the opposite sides of said shaft to discharge above the latter and communicating with said chamber between the ends of the latter and the middle thereof, and a charge of size-reducing medium in said chamber.

5. In a mill, a frame, a hollow shaft supported by said frame for pivotal movement, means for oscillating said shaft on its axis through a pre-

determined arc, a casing surrounding said shaft and secured thereto for movement therewith, said casing having an opening through the upper portion thereof and a plurality of other openings of which one at least is below said shaft in the mid-position of the oscillatory movement of said shaft, means connecting the interior of said shaft with said last mentioned opening, a size-reducing chamber member carried by the lower part of the casing and providing a size-reducing chamber communicating adjacent its middle with said last mentioned opening and further communicating at points spaced from its middle with the remainder of said plurality of openings, and a charge of size-reducing medium in said chamber.

6. In a mill, a frame, a hollow shaft mounted in said frame for rotary movement, a casing around said shaft and secured thereto for movement therewith, said casing being generally cylindrical and having an opening through the upper portion thereof and three openings through the lower wall thereof, means connecting the interior of said shaft with one of said openings, a size-reducing chamber member carried by the lower part of said casing and providing a size-reducing chamber communicating adjacent its middle with the last mentioned one of said openings and adjacent its ends with the other two openings, and a size-reducing medium charge in said chamber.

7. In a mill, a frame, a hollow shaft mounted in said frame for rotary movement, a casing around said shaft and secured thereto for movement therewith, said casing being generally cylindrical and having an opening through the upper portion thereof and three openings through the lower wall thereof, means connecting the interior of said shaft with one of said openings, a size-reducing chamber member carried by the lower part of said casing and providing a size-reducing chamber communicating adjacent its middle with the last mentioned one of said openings and adjacent its ends with the other two openings, said last mentioned openings being gridded openings.

8. In a mill, a frame, a hollow shaft mounted in said frame for rotary movement, a casing around said shaft and secured thereto for movement therewith, said casing being generally cylindrical and having an opening through the upper portion thereof and three openings through the lower wall thereof, means for feeding material to be processed into said shaft, means connecting the interior of said shaft with one of said openings, a size-reducing chamber member carried by the lower part of said casing and providing a size-reducing chamber communicating adjacent its middle with the last mentioned one of said openings and adjacent its ends with the other two openings, and a size-reducing medium charge in said chamber.

9. In a mill, a frame, a hollow shaft mounted in said frame for rotary movement, a casing around said shaft and secured thereto for movement therewith, said casing being generally cylindrical and having an opening through the upper portion thereof and three openings through the lower wall thereof, means for admitting air and feeding material to be processed into said shaft, means for placing the space between said shaft and casing under suction, means connecting the interior of said shaft with one of said openings, a size-reducing chamber member carried by the lower part of said casing and providing a size-reducing chamber communicating adjacent its middle with the last mentioned one of said openings and adjacent its ends with the other two

openings, and a size-reducing medium charge in said chamber.

10. In a mill, a frame, a hollow shaft mounted in said frame for rotary movement, a casing around said shaft and secured thereto for movement therewith, said casing being generally cylindrical and having an opening through the upper portion thereof and three openings through the lower wall thereof, a paddle secured to said shaft at the upper side thereof and dividing the upper part of the interior of said casing into two chambers, means connecting the interior of said shaft with one of said openings, a size-reducing chamber member carried by the lower part of said casing and providing a size-reducing chamber communicating adjacent its middle with the last mentioned one of said openings and adjacent its ends with the other two openings, and a size-reducing medium charge in said chamber.

11. In a mill, a supporting framework, a hollow shaft journaled thereon, a pendulum supported by said shaft and providing an arcuately elongated size-reducing chamber, said hollow shaft having feeding means communicating therewith, passage means connecting said hollow shaft with said size-reducing chamber adjacent the middle of the latter, the communication of said feeding means with said shaft spaced longitudinally of said shaft from the communication with the latter of said passage means, a charge of size-reducing medium in said chamber, and means for imparting to said pendulum an arcuate oscillation of an angular amplitude a fraction of the angular arcuate extent of said chamber, said chamber having discharge means adjacent each end thereof opening through the bottom thereof.

12. In a mill, a supporting frame, a pendulum pivotally supported on said frame for oscillating movement and having a shaft constituting means for supporting the same during oscillation, said pendulum providing walls bounding and defining a size-reducing chamber arcuate in the planes of oscillation of said pendulum and a communicating feed passage extending radially of the pendulum and opening into the size-reducing chamber between the ends of the latter, the walls bounding said feed passage being continuous and imperforate save for a lateral opening providing for the introduction, during the size-reducing operation, of material in a direction transverse to the planes of oscillation of said pendulum from a point outside said planes laterally into the latter and adjacent the pivotal axis thereof, said opening lying within said shaft, and power means for rapidly oscillating said pendulum.

13. In a mill, a size-reducing-chamber-providing member mounted for swinging movement upon a substantially horizontal axis and providing an arcuate chamber having concentric inner and outer walls and of such extent and curvature that a straight line connecting the central points in the ends of said chamber falls at its middle point radially inside the central point in the curve of the inner wall of said chamber, means for supplying material to said chamber during oscillation thereof and for discharging processed material therefrom also during operation, and means for oscillating said member rapidly about its pivot through a path both of whose extremities lie below a horizontal plane including said horizontal axis.

14. In a mill, a movably mounted size-reducing chamber supported for swinging in opposite directions about an axis, said chamber elongated and substantially arcuate in its planes of move-

- ment and of a uniform width internally throughout its length and of comparatively small but uniform dimension normal to its path of swing, means for introducing material into said chamber including a feed opening substantially midway between its ends, a feed passage surrounding the axis about which said chamber swings, and means for delivering material into said feed passage through an end and longitudinally thereof, means for discharging processed material while said chamber is in motion, and means for moving said chamber oppositely along said path, the length of said chamber, its dimension normal to its path, the dimension of said feed opening longitudinally of said chamber and the rate and amplitude of movement of said chamber such that when said mill is operating at capacity during each movement of said chamber in one direction along its path the same is filled completely full throughout the central zone of its length while both ends thereof are empty, whereby the chamber contents control the feed.
15. In a mill, means providing a reversely arcuately moved chamber arcuate in its planes of movement and of substantially uniform cross sectional area on planes including the axis of movement of such chamber at substantially all points between its end portions, means for feeding material to said chamber including a feed inlet for 20 entering material for conducting such material from a point outside said planes of movement laterally of the mill into such planes, passage means communicating at one end with said feed inlet and surrounding for at least the width of 25 the chamber the axis of movement of said chamber for conducting such material longitudinally of the axis of movement of said chamber, and a feed connection opening into said passage means and terminating in an intake opening through 30 a wall of said chamber, and a charge of free size-reducing media in said chamber, said size-reducing media and material admitted through 35 said feed opening forming a mass moving as a whole from end to end of said chamber and traveling alternately back and forth across said 40 opening while said mill is in operation and acting as a gate therefor.
45. In a mill, a supporting frame, a member pivotally supported on said frame for swinging movement and providing walls, including ra-

5 dially-spaced, curved, longitudinally-extending walls struck from a common axis perpendicular to the planes of swing of said member, bounding and defining a size-reducing chamber arcuate in the planes of swing of said member and of uniform cross-sectional area on radial planes at substantially all points between its end portions, means forming a feed passage including a portion extending normally to the arc of said chamber and opening into said chamber between the ends 10 of the latter and a portion for delivering material to said first mentioned portion, said second portion extending in a direction transverse to the planes of swing of said member and surrounding and conducting material longitudinally of the 15 axis of swing of said member from a point outside the planes of swing of said member into such planes, and power means for rapidly oscillating said member.

17. In a mill, an arcuate oscillatably supported 20 chamber of an arcuate extent less than 360° and of substantially uniform cross sectional area on radial planes including the axis of chamber oscillation and cutting the chamber between its end portions, said chamber having concentric walls at 25 its sides respectively nearest and most remote from said axis and said walls each being provided with discharge openings for material reduced in size within said chamber, means for introducing material into said chamber through the wall 30 nearer said axis at a point adjacent the longitudinal center of said wall, and means for imparting to said chamber rapid oscillation of an arcuate extent materially less than the angular extent of said arcuate chamber. 35

18. An oscillating, elongated, size-reducing chamber having arcuate top and bottom walls of concentric curvature, said chamber of approximately uniform cross section at all points between its end portions on planes normal to said 40 walls and said chamber having an inlet in said top wall but spaced from the ends thereof for material to be processed and said chamber also having orifices for the discharge, while said chamber is in motion, of processed material in 45 the bottom wall thereof and also in the top wall in the portions of the latter between said inlet and the ends of said top wall.
